US00D389096S

United States Patent [19]

Tako et al.

[11] Patent Number: Des. 389,096

[45] Date of Patent: **Jan. 13, 1998

[54] MOTORCYCLE

[75] Inventors: Kenji Tako; Yukinori Kawaguchi, both of Saitama, Japan

9254231	6/1995	Japan .
927295	6/1995	Japan .
9256201	10/1995	Japan .
937981	10/1995	Japan .

[73] Assignee: Honda Giken Kogyo Kabushiki Kaisha, Tokyo, Japan

[**] Term: 14 Years

[21] Appl. No.: 61,896

[22] Filed: Nov. 1, 1996

[30] Foreign Application Priority Data

Jun. 17, 1996 [JP] Japan 8-17931

[51] LOC (6) Cl. 12-11

[52] U.S. Cl. D12/110
